CLAIM

The ornamental design for a golf club head for a putter, as shown and described.

DESCRIPTION

FIG. 1 is a top perspective view of a golf club head for a putter showing my new design;

FIG. 2 is a front view thereof;

FIG. 3 is a rear view thereof;

FIG. 4 is a toe end view thereof;

FIG. 5 is a heel end view thereof;

FIG. 6 is a top plan view thereof; and,

FIG. 7 is a bottom plan view thereof.

The broken line showing that is immediately adjacent to the shaded area represents an unclaimed boundary of the design. The broken line showing of the remainder of the golf club head for a putter is for illustrative purposes only and forms no part of the claimed design.
